FIG.3.

INVENTOR:

W. T. Stall
High-top Sporting Shoe
ATTYS.

UNITED STATES PATENT OFFICE.

WALTER T. STALL, OF BROCKTON, MASSACHUSETTS, ASSIGNOR TO WALTER T. STALL AND CHARLES H. DEAN, BOTH OF BROCKTON, MASSACHUSETTS, COPARTNERS DOING BUSINESS AS STALL & DEAN MANUFACTURING COMPANY.

SPORTING-SHOE.

1,212,834.

Specification of Letters Patent. Patented Jan. 16, 1917.

Application filed March 9, 1916, Serial No. 83,051. Renewed November 29, 1916. Serial No. 134,209.

To all whom it may concern:

Be it known that I, WALTER T. STALL, a citizen of the United States, residing at Brockton, in the county of Plymouth and State of Massachusetts, have invented new and useful Improvements in Sporting-Shoes, of which the following is a specification.

This invention relates to shoes to be worn by players of basket ball, tennis, etc., the shoe comprising an outer sole of elastic material and a body of leather or other suitable non-vulcanizable and practically inextensible material, said body including an upper, an inner sole, and fastenings uniting said parts.

The object of the invention is to provide an improved connection between the rubber outer sole and the body of a shoe of this character, and consists in the improvements which I will now proceed to describe and claim.

Of the accompanying drawings forming a part of this specification: Figure 1 represents a side view of a shoe embodying my invention; Fig. 2 represents a bottom view of the same; Fig. 3 represents a section on line 3—3 of Fig. 1.

The same reference characters indicate the same or similar parts in all the views.

In the drawings, 12 represents an outer sole of elastic rubber or a composition containing rubber, the sole being preferably relatively thick and compressible so that it will cling to a floor or other surface on which the wearer stands. 13 represents a flange of inelastic and substantially inextensible material, such as duck or canvas, suitably prepared to be attached by vulcanization to the outer sole 12.

40 The flange 13 is preferably formed to cover the edge of the outer sole 12, as shown and is vulcanized to the portion of the sole on which it bears, the flange projecting upwardly from the sole.

45 The body of the shoe is made of non-vulcanizable material such as leather, and includes an upper 15, an inner sole 16, and fastenings such as stitches uniting said parts. The body may also include a sole 50 lining 17.

The upwardly projecting flange 13 surrounds the united portions of the upper and inner sole, overlaps the lower portion of

the upper, as shown, and is united thereto by suitable fastenings, such as stitches 18, 55 located above the inner sole.

It will be seen that my improvement above described provides a strong and durable connection between a rubber outer sole and a leather shoe body, and that the outer sole and the inextensible flange may be united by vulcanization before application to the shoe body, and constitute a bottom having a recess at its upper side to receive the lower portion of the body. It will also be seen that the recessed bottom is applicable to the body as a single piece or part, and is attachable thereto by the fastenings 18 after the completion of the body. The upper surface of the outer sole forms the 70 bottom and the flange 13 the margin of the recess.

The bottom attached to the shoe body only by the stitches 18, uniting the flange to the upper, is composed of but two pieces, 75 viz., the one-piece outer sole and the flange. Said bottom is removable as one part when said stitches are removed, so that when the outersole portion of the bottom is worn out, the stitches may be cut and the bottom removed and replaced by a duplicate bottom, without discarding anything but the two pieces forming the bottom.

The joint formed by the vulcanization of the textile fabric strip to the edge of the 85 sole is substantially in alinement with the projecting portion of the strip which forms the flange 13, hence said joint is well adapted to resist strain tending to displace the strip edgewise. 90

The described shoe bottom constitutes a new article of manufacture.

Having described my invention, I claim:

1. A shoe having an inelastic non-vulcanizable body comprising an insole and an upper, and an elastic removable bottom composed of a one-piece rubber outer sole and a continuous upwardly projecting textile fabric flange bearing on and vulcanized directly to said outer sole, surrounding the 100 insole and the lower marginal portion of the upper, and secured to the upper by exposed stitches, said bottom being attached without vulcanizing heat, and separable as one part from the body when said stitches are 105 removed.

2. As an article of manufacture, a shoe bottom composed of a one-piece rubber outer sole and a continuous upstanding textile fabric flange bearing on and vulcanized directly to said outer sole, and adapted to hold attaching stitches engaged with the marginal portion of a shoe upper, so that the rubber outer sole may be renewably secured to a shoe body.
- 5 3. As an article of manufacture, a shoe bottom composed of a one-piece rubber outer sole and a continuous strip of textile fabric
- wider than the thickness of the sole, covering and vulcanized to the edge of the sole and projecting above the sole to form a flange adapted to be stitched to the marginal portion of a shoe upper, the joint formed by the vulcanization of the strip to the edge of the sole being substantially in alignment with the projecting portion of the strip.
- 10 In testimony whereof I have affixed my signature.

WALTER T. STALL.
